UNITED STATES PATENT OFFICE.

HENRY A. HOLDREGE, OF CHICAGO, ILLINOIS.

TELEPHONE-METER.

SPECIFICATION forming part of Letters Patent No. 690,289, dated December 31, 1901.

Application filed June 3, 1901. Serial No. 62,873. (No model.)

To all whom it may concern:

Be it known that I, HENRY A. HOLDREGE, a citizen of the United States, residing in Chicago, in the county of Cook and State of Illinois, have invented a new and useful Improvement 5 in Telephone-Meters, of which the following is a specification.

The object of the present invention is a telephone-meter for counting and registering the 10 number of completed connections made at the central exchange by each individual telephone subscriber with any other subscriber.

The prime object of the invention is to so contrive the electrical devices and circuits 15 that an individual subscriber may call the central office for a connection in the usual manner, be answered by the central office, and the usual attempt be made at the central office to secure the desired connection without 20 operating the register, which latter is not operated until the called subscriber has been put in connection with the calling subscriber and not then until the connection thus made has been broken by the act of the operator 25 at the central office in removing the answering-plug. The arrangement is such that only the first step toward the operation of the registering device is taken when the connection between the two subscribers is completed, the registration itself being completed 30 only when that connection is broken. This is accomplished by means of a polarized relay operating in connection with each of the electromagnetic registers (one for each subscriber) and a reversing-relay in each of the 35 cord-circuits at the central office in conjunction with the usual circuits and instruments now commonly in use, and herein consists the invention, generally stated.

40 The accompanying drawing, which forms a part of this specification, shows in diagrammatic form the invention in connection with a central station and two subscribers' telephones.

45 In said drawing, A represents what we may suppose to be a calling-subscriber's telephone and the electrical and mechanical apparatus there situated.

50 B, in like manner, represents what may be supposed to be the telephone of the called subscriber.

All the other circuits and apparatus shown

on the diagram may be supposed to be located at the central station.

In order to distinguish more clearly the devices and parts and circuits which are now commonly in use from those which have been changed or added in furtherance of the present invention, the latter have been marked upon the diagram in dotted lines, while the 55 former or old parts and circuits are shown in full lines. With reference to the well-known parts shown in the diagram it will be sufficient to state that a represents the calling-subscriber's transmitter; a', his receiver; a², 60 his call-bell; a³, his condenser, and a⁴ a⁵ the two parts of his line-wire, while b, b', b², b³, b⁴, and b⁵ are corresponding parts of the receiving-subscriber's apparatus, and in like manner at the central station c is the operator's transmitter; c', the operator's receiver; c², 65 the ringing-generator, and c³ the operator's condenser.

D is the usual ringing-switch; D', the usual listening-switch; E and E', the usual supervisory relays; F, the repeating-coil; G G', the call-signal lights; H H', the supervisory-signal lights; J, the answering-plug, and J' the connecting-plug.

K K' are the answering-jacks for receiving 80 the answering-plug, and L L' are the connecting-jacks for receiving the connecting-plug.

M M' are the cut-off relays, and N N' the call-relays.

O is the battery.

85 Thus far described the apparatus is precisely such as is in common and general use in many telephone systems now in operation.

Referring now to the parts which have been added and which are shown in dotted 90 lines, P is a reversing-relay—that is to say, an electromagnet which when energized operates a switch or switches in such manner as to reverse the direction of the current through the line controlled by said switch or 95 switches.

Q is a polarized relay, the current through which is controlled by the reversing-relay above mentioned.

R is the registering-magnet, the armature 100 R' of which is connected to the mechanism of the register S.

T is an extra contact-point at the cut-off relay for closing the circuit through the reg-

istering-magnet R when the cut-off relay is energized.

U is a contact device for the armature R' of the register-magnet, which is closed when the register-magnet is energized and the register operated for cutting out the operation of the polarized relay.

The operation of the circuit and apparatus is as follows: Suppose the subscriber at station A removes his receiver from its hook and by that act closes the circuit through his main line to the central office. The circuit will then pass through the call-relay N, which will close the circuit through the call-signal light G, whereby the operator at the central office is warned of the call. The central operator will then insert the answering-plug J into the answering-jack K, which energizes the cut-off relay M and by causing the movement in its armature closes contact at the contact-point T. At the same time and by the same energy the cut-off relay disconnects in the usual manner, as will be seen, the circuit to the call-signal light G. The central operator is now in position to talk to the calling subscriber, as will be readily understood, and, having ascertained, for example, that a connection with the subscriber B is required, inserts the connecting-plug J' in the connecting-jack L', and at the same time closes the ringing-switch D, which signals the subscriber B by ringing his bell. Now when the subscriber B takes down his telephone, and thus closes his circuit, shunting his condenser ^{b3}, the effect is to energize the supervisory relay E', and thus close the circuit through the reversing-relay P, which reverses the circuit through the polarized relay Q and causes it to swing its armature and close contact at contact-point q, whereby the circuit is closed through the register-magnet R, and its armature R' is thus brought into contact with the contact-point U, so that the circuit will be maintained through the register-magnet R thereafter, even though it shall be broken through the polarized relay, and will continue thus so long as the contact remains unbroken at the contact-point T. This is important, because it may happen that the operator at the central station or the subscriber at either of the subscribers' stations may break the circuit by moving the telephone-hook or by the central operator at the central station by removing the connecting-plug J', any of which things may be done in this arrangement and under such circumstances without deenergizing the register-magnet R. However, when the subscribers are through talking and one or both of their receivers are hung up and their circuit thus broken and the central operator finally removes the answering-plug J the contact at the contact-point T is thus broken and the register-magnet R thus thrown out of circuit completely or deenergized, and the armature-spring s then comes into action and withdraws the armature R', to which is connected the

rod s', which enters the register S and operates the same mechanically to move the register-wheels, and thus register an additional number or unit. It will not be necessary to describe the mechanism inclosed in the register, as any well-known counting mechanism operated by a single mechanical impulse may be employed.

From the foregoing it will be seen that each complete connection had by any one subscriber with any other is automatically registered without any special or unusual action of either the calling or called subscriber being required and that this takes place only after the connection has been completely made at the central office and finally broken at the central office, and, moreover, requires no special manipulation on the part of the operator at the central office beyond the usual manipulations now required, and, furthermore, in no way interferes with the operation of the usual signaling devices now commonly employed, so that the register will indicate, and only indicate, completed calls where the calling and called subscribers have been in actual communication, and such registration cannot be produced or brought about by any act of the subscriber or subscribers alone nor by any act of the operator at the central office alone, but requires the joint action of the operator at the central office and two subscribers, so that perfect assurance is given that the register will indicate automatically exactly what is desired shall be registered, and all of this without any special manipulation on the part of the subscriber or of the central operator, and all of this, too, notwithstanding any attempt that may be made by either subscriber or operator, to signal each other or the central office by manipulating the telephone-hook.

In the central upper portion of the diagram three unlettered resistance-coils are shown. This is an old device already in use in conjunction with supervisory-signal lights, such as H and H', which have been heretofore used in a similar relation. Such signal-lights are commonly constructed to burn on a difference of potential of twelve volts. The battery of the exchange is ordinarily constructed to supply about twice that voltage. Now the two upper unlettered resistance-coils in the diagram are connected, it will be seen, in series with the lamps, and thus deliver the proper current to the signal-lights when said signal-lights are burning. Now when the supervisory relay E is energized and its armature drawn up the lowermost one of the three unlettered resistance-coils is brought into a shunt-circuit around the lamp H, so that a portion of the current to said lamp is thereby diverted from said lamp and the lamp thereby dimmed or nearly extinguished. The coil on the reversing-relay P serves as a similar resistance for dimming the signal-lamp H' when the supervisory relay E' is energized. The general purpose of this arrangement is to enable the operation of the two signal-

lights after the plugs J or J' are inserted in their respective jacks without breaking the circuit through said plugs—in other words, to enable the operation of the signal-lights as required and at the same time maintain the circuit through the plugs. I do not claim to have invented this arrangement, which is a well-known one, but merely insert this description so that the construction illustrated in the diagram may be understood.

I claim—

1. In a telephone system consisting of a central office and two or more subscribers' telephone-stations, the combination with the instruments and circuits thereof, of a mechanical registering device, a register-magnet for operating the same, a polarized relay which controls the register-magnet, and a reversing-relay which controls the polarized relay, substantially as specified.
2. In a telephone system consisting of a central office and two or more subscribers' telephone-stations, the combination with the instruments and circuits thereof, of a mechanical registering device, a register-magnet for operating the same, a polarized relay which controls the register-magnet, a reversing-relay which controls the polarized relay, and a supervisory relay which controls the register-relay, the latter being energized and controlled by the closing of the circuit at the called-subscriber's telephone, substantially as specified.
3. In a telephone system consisting of a cen-

tral office and two or more subscribers' telephone-stations, the combination with the instruments and circuits thereof, of a mechanical registering device, a register-magnet for operating the same, a polarized relay which controls the register-magnet, a reversing-relay which controls the polarized relay, and a circuit closed by the armature of the register-magnet, whereby after said register-magnet has acted a reversal or interruption of the circuit through the polarized relay cannot break the circuit through the register-magnet, substantially as specified.

4. In a telephone system consisting of a central office and two or more subscribers' telephone-stations, the combination with the instruments and circuits thereof, of a mechanical registering device, a register-magnet for operating the same, a polarized relay which controls the register-magnet, a reversing-relay which controls the polarized relay, and a switch in the line to the register-magnet, as for example the armature of the cut-off relay, which magnet is controlled by the answering-plug of the central operator, whereby the removal of said answering-plug will break the circuit through the register-magnet and permit the registration to take place, substantially as specified.
